UNITED STATES PATENT OFFICE

2,254,804

CONVEYER FOR CLASSIFIERS

Alfred E. Johnson, Denver, Colo., assignor to
 Morse Bros. Machinery Company, Denver,
 Colo., a corporation of Colorado

Application May 18, 1939, Serial No. 274,415

3 Claims. (Cl. 198—224)

This invention relates to improvements in classifier mechanism and more particularly to classifiers designated commercially as the rake-type.

In certain industries, for example in mining, where ore is reduced to separate and obtain the valuable constituents therefrom, it is frequently necessary to separate settled solids from a liquid pulp. In the reduction of such mineral ores, the ore is typically reduced in size by a grinding process to liberate valuable constituents thereof, and during or after the reduction, the ground product may be mixed with water to form a "pulp."

There are also other industrial processes requiring the separation of divided solids of certain size or weight from other solids and/or from liquids. A classifier may be used for such separation in any process where materials are so classified. The present invention is not limited to mining nor to the separation or classification of mineral ores.

In the mining industry, in order to separate the coarse particles of ore commonly called the "sands," from the rest of the pulp, the mixture commonly is subjected to such a classifying treatment. Usually this classifying step consists in forming a substantially static pool of the pulp permitting the larger and/or heavier particles of ore or "sands" to settle onto an inclined surface, whereupon such settled sands are raked upwardly along the inclined surface to a point of discharge at an elevation above the surface of the pool. The separated and discharged sands may then be subjected to further treatment, such as returning to the grinding media for further reduction.

The present invention discloses improved mechanism for accomplishing this important classifying step in ore reduction or in any other industry requiring such a process.

A particular object of the present invention is to provide mechanism for reciprocating a rake element in a classifier in an unusually advantageous movement.

Another object is to provide a classifier having a highly simplified operating mechanism.

A further object is to provide in a classifier, rake carrying and operating mechanism that readily may be used optionally to control the clearance between the rake and the upwardly inclined sand-bearing surface, adjacent which the rake operates.

Still another object of this invention is to provide classifier mechanism that may be used in

5 a simplex form as explained hereinbelow, or in a balanced duplex arrangement as will be more fully set forth.

Still another object is to provide a simplex 10 rake-reciprocating mechanism that is well balanced mechanically to facilitate its operative functions.

Other objects and advantages reside in details of design and construction which will be more fully disclosed in the following description and in the drawings wherein like parts have been similarly designated and in which:

15 Figure 1 is a plan view of a typical single or "simplex" classifier mechanism embodying the present inventive concept;

Figure 2 is a fragmentary side elevation of the same, drawn partially in section for purpose of clarity;

20 Figure 3 is a plan view of a duplex classifier made according to this invention;

Figure 4 is a fragmentary end elevation looking in the direction of arrow 4 in Figure 2;

25 Figure 5 is a fragmentary detail view of an optional modification that is particularly adapted for use on classifiers of the type illustrated in Figures 1 and 2;

Figure 6 is a diagrammatic illustration of the 30 path of differential reciprocation of the rake elements illustrated in Figures 1, 2, 3 and 4;

Figure 7 is a fragmentary view illustrating a 35 preferred modification of certain specific details.

In order completely to disclose a typical example of a reduction to practice of the present invention, reference in detail will be had to the 40 component parts of the classifiers herein illustrated. Reference character 12, Figures 1 and 2, denotes a typical classifier tank having a pool-forming lower end 13, an upwardly inclined bottom 14 and a discharge end at 15. The tank 12 and the operative mechanism conveniently may be supported by any suitable structure designated as a whole by reference character 16.

45 A prime mover such as an electric motor 17, drives a pulley 18 by means of belting 19. The driven pulley 18 is carried on a shaft 20 which carries adjacent its opposite end a pinion 21 meshing with a driven gear 22 carried on a shaft 23. Shaft 23 being thus rotated at a reduced speed, drives a crank disk 24, the crank 50 25 of which engages and reciprocates a frame 26. Frame 26 may be made of any suitable structural material and is herewith illustrated as being made of standard channel steel members. The frame 26 is composed of a lower or rearward section 26a and an upper or forward

section 26b. The two sections are connected by the crank pin 25 for simultaneous but differential reciprocation.

The lower or rearward frame section 26a is supported for differential reciprocation upon pivotal links 27 and the upper or forward frame section 26b is supported for differential reciprocation upon pivotal links 28. The rearward links 27 are carried upon movable arms 29 mounted upon a shaft 30 which may be rotated to impart angular movement to the arms 29 through the intermediary of a gear sector 31 operated by a worm 32 connected for manual rotation by means of a handwheel 33. Obviously, by rotating the handwheel 33, the movable arms 29 may be raised or lowered along arcuate paths, thus to raise or lower the axis of oscillatory movement of the links 27.

The frame structure 26 is pivotally connected with a rake element 133 to support and reciprocate the rake. The rearward or lower end of the frame structure 26 is pivotally connected with the rake 133 by means of plates 34 and a shaft 35 carried on said frame section 26a. The upper or forward end of the frame structure 26 is connected with the forward end of the rake 133 by means of a pivotal yoke 36 engaging in keyhole slots 37 in plates 38 which are attached to the rake as by means of rivets 39. The yoke 36 is pivotally carried on a shaft 36a, which in turn is mounted on frame section 26b.

From the foregoing description and the accompanying drawings referred to therein, it readily will be seen that by rotation of the crank pin 25 the frame 26 will be differentially reciprocated and will in turn impart a very specialized differential movement to the rake member 133. The path of the rake as it is differentially reciprocated is approximately illustrated diagrammatically in Figure 6. Such a path of movement is highly desirable because the rake element 133 is caused to move upwardly and forwardly in controlled spaced relationship with the inclined bottom 14 of the tank 12. The upward and forward movement of the rake is substantially parallel to said bottom 14 so that the material being raked upwardly therealong may be contacted by the rake.

When the rake element reaches the forward-most position of its straight line movement along the inclined surface 14, the mechanism hereinabove set forth acts to raise the rake element away from the inclined bottom 14 and the material thereupon, so that it is returned to its rearwardmost position without the danger of it dragging the sands back toward the pool. From such rearwardmost position, the rake is lowered toward the inclined surface 14 to begin again its upwardly inclined straight line movement parallel to the sand-bearing inclined surface 14.

The handwheel 33 may be used to vary the clearance between the rake and the inclined surface 14 and also to vary the exact pattern of the path of the differential reciprocating movement of the rake element. The single rake mechanism as illustrated in Figures 1 and 2, is known as a simplex classifier.

Next, referring to Figure 3, the classifier tank is divided into two parallel and similar tanks 12a and 12b. It appears unnecessary to illustrate a side elevation of the mechanism shown in Figure 3 because its general arrangement and organization as viewed from the side would be very similar to Figure 2.

The mechanism illustrated in Figure 3 is driven

through the intermediary of a shaft 20a and a pinion carried thereon and meshing with the gear 22a carried on a shaft 23a, which is provided with two crank disks 24a and 24b.

As illustrated, the cranks on crank disks 24a and 24b are in diametrically opposite positions at all times so that the mechanism is very well balanced both statically and dynamically. Crank disk 24a reciprocates a frame structure 126 and crank disk 24b reciprocates a frame structure 126a, both of said frame structures being similar to the frame structure 26 hereinabove set forth.

The rearward or lower ends of both frame structures 126 and 126a are mounted upon oscillatory links similar to links 27 and given reference character 27a, and the upper or forward ends of the frame structures 126 and 126a are carried upon links similar to links 23 and designated by reference character 28a. The frame structure 126 carries a rake element 133a. The details of the connections between frame 126 and rake 133a are similar to the construction hereinabove set forth. The frame 126a carries a rake element 133b and is connected therewith as above described.

It appears obvious that the rakes 133a and 133b will be differentially reciprocated along paths similar to the diagrammatic illustration of Figure 6 and as these two rakes are reciprocated side by side, they will be at opposite points along their reciprocating paths at all times.

The double or duplex classifier illustrated in Figure 3 has twice the capacity of the classifier illustrated in Figure 1 and, as above pointed out, the mechanism is well balanced at all times. Both the simplex and duplex classifiers are exceptionally well adapted to perform the classifying function of raking sands upwardly along an inclined surface away from and out of the settling pool.

In the simplex machine, it is sometimes desirable to artificially balance the reciprocating mechanism. One good way to balance the simplex mechanism is to use a counterweighted crank disk such as illustrated in Figure 5, in place of the symmetrical crank disks illustrated in Figures 1, 2, 3 and 4.

The crank disk illustrated in Figure 5 is carried upon a shaft 23b and is provided with a counterweight 40 diametrically opposite the crank pin 41. Obviously, in such an arrangement, the counterweight 40 tends to counterbalance the weight supported upon the crank pin 41.

The simplex mechanism as illustrated in Figures 1 and 2, is more likely to require counterbalancing than the duplex arrangement. Obviously, other arrangements could be had for counterbalancing the simplex mechanism and a counterweight could be placed advantageously upon some other part of the mechanism to be effective in its counterbalancing function. Due to the leverage involved in frame sections 26a and 26b, it might under some circumstances be desirable to position the counterweight on the same side of the shaft 23b as the crank pin.

The sections of the several frame structures 26, 126 and 126a act as levers wherein the actuating power is supplied at and by the crank pins with which they are connected, the load is the rake elements and the levers are fulcrumed on the oscillatory links as set forth. The resultant movement of the supported rake elements is approximately as illustrated in Figure 6 and is highly efficient in moving material along a sur-

face associated with such a rake element so moved.

Figure 7 is a fragmentary view illustrating a preferred modification of the manual lifting device for the rake-operating mechanism. The gear sector 31 is keyed to the shaft 30 as hereinbefore set forth, and the movable arms 29 are mounted upon said shaft 30 and carry the oscillatory links 27. The worm 32 is manually operable by means of the handwheel 33 and is carried upon a special yoke 50 that is rotatably carried upon the shaft 30. The rotatable yoke 50 has a projection 51 that is positioned to contact a stop 52 carried upon the structural member 16. Obviously, when the worm 32 is rotated in a direction to force gear sector 31 downwardly to raise arms 29, the yoke 50 will tend to move upwardly bringing the part 51 thereof into engagement with the stop 52, thus holding the yoke in the illustrated position and enabling the worm 32 to serve its purpose of elevating the arms 29 and the links 27. If and when some foreign obstacle should get in the way of the rake, the yoke 50 will pivot downwardly permitting the arms 29 to raise from their normal position, thus permitting the rake to raise and prevent damage thereto.

It is now apparent that the stated objects of this invention are fully accomplished by the example of reduction to practice herein set forth and, further, that this inventive concept represents an important forward step in the art of building and successfully operating classifiers or the like. While this specification discloses preferred means for reducing the present invention to practice and a preferred embodiment of the invention, changes may occur to those skilled in the art and may be made within the scope of the appended claims, without departing from this inventive concept.

What I claim and desire to secure by Letters Patent is:

1. In a classifier having an inclined surface for divided solids and a rake, the improvement which comprises mechanism for operating said rake adjacent said surface inclusive of a sectional frame

above the surface, oscillatory links carrying the sections of said frame, means for reciprocating the frame on said links, means connecting the sections of said frame with the rake, angularly 5 movable arms supporting the links that carry one of said frame sections, a gear sector for moving said arms, a manually operable worm engaging the gear sector, an angularly movable yoke supporting the worm, and a relatively stationary stop positioned to limit the movement of said yoke.

10 2. In a classifier having a rake, the improvement which comprises means for supporting a portion of the rake inclusive of a shaft, an arm solidly mounted upon the shaft and supporting a portion of the rake, a gear sector solidly mounted upon said shaft, a yoke mounted for rotation about the axis of said shaft in one direction, stop means positioned adjacent said yoke for limiting its rotation in the other direction, and means 15 carried upon said yoke and engaging said gear sector for rotating the shaft.

20 3. In a classifier or the like having an upwardly inclined surface for the support of divided solids, the improvement which comprises a crank pin journalled for rotation above said surface,

25 means for rotating the crank pin, a frame section pivotally connected adjacent one of its ends with said crank pin, a yoke pivotally suspended at the other end of the frame section, plates having key-hole slots pivotally hung from said yoke, oscillatory arms supporting the frame section intermediate said end portions, a second frame section pivotally connected adjacent one of its ends with the crank pin, other plates pivotally connected with the second frame section adjacent

30 its other end portion, oscillatory links supporting said second frame section intermediate its end portions, a rake element supported on said plates in a position to move upwardly adjacent said inclined surface and parallel thereto and to be returned downwardly away from said surface

35 thus to complete a differential cycle of movement, and means for balancing said mechanism.

40 ALFRED E. JOHNSON.
